FILING CABINET JOINT

Jack Adler, St. Louis, Mo.

Application April 14, 1952, Serial No. 282,254

4 Claims. (Cl. 312—257)

1

This invention relates to improvements in sheet metal filing cabinets and more specifically to a construction for joining several of the essential elements of the same into a rugged and firmly interlocked relation to enable the cabinet to withstand normal usage over unusually long periods of time without becoming wobbly or otherwise unstable.

One of the principal objects of my invention is to construct the interlocking elements in such a manner that the factory assembly of the cabinets may be done economically, rapidly, and easily on the usual production line basis of commercial practice.

The invention has among its other objects the production of such a joint that will be neat and simple, have a minimum of extraneous fastening elements, and which will be otherwise satisfactory and efficient for use wherever deemed applicable.

Many other objects and advantages of the construction herein shown and described, and the uses mentioned, will be obvious to those skilled in the art to which the invention appertains, as will be more clearly disclosed herein.

In the drawings, wherein like reference characters represent like or corresponding parts throughout the views,

Figure 1 is a fragmentary perspective view of a filing cabinet structure, showing the joint between the side wall, front rail and slide rail;

Figure 2 is a side elevation of a fragment of the side wall adjacent said joint, and showing a portion of the front rail interlocked in assembled position;

Figure 3 is a cross-sectional detail, taken substantially along the line 3—3 of Fig. 1;

Figure 4 is a perspective detail of one end of the front rail; and

Figure 5 is a perspective detail of the end of the slide rail that interlocks with the front of the side wall.

Referring more particularly to the drawings, wherein I have illustrated a preferred embodiment of my invention, there is shown only that portion of a sheet metal filing cabinet to which my invention is directed, the remaining portions of the cabinet not being shown inasmuch as they may be of any standard or special construction.

Such a cabinet is generally prismatic in shape, one of the vertical side walls 1 being shown, the forward portion of said wall being first bent to provide a relatively narrow vertically extending front face 2 and then bent reentrantly so that the free edge 3 of the reentrant flange 4 is directed toward the rear of said side wall for a

short distance. If desired, said free edge may be provided with a slight rib 5 close thereto and extending the height of said wall.

At about each vertical interval where it is desired to locate the drawer-receiving slide rails 6, there being two such intervals in the event that the cabinet is to receive two horizontally slidable drawers, and three such intervals where three drawers are to be received, the flange is provided with an approximately horizontally extending and rearwardly directed slot whose lower portion is indicated at 7 and whose upper portion is indicated at 8, it being noticed that the front and rear ends of said slot is closed and terminating short of the corresponding vertical edges of the flange for a purpose to be more clearly hereinafter described, the rear end terminating adjacent the rib 5. Said slot is wider at its rear than at its front and it is to be especially noted that the upper portion of said slot extends rearwardly beyond the rear end of the lower portion of said slot.

The front rail element 9, that defines the drawer-receiving openings into the cabinet in the usual manner, and which is assembled into position so as to extend horizontally across the cabinet between a pair of side walls of the latter, may be of channel cross-sectional shape if desired, and provided with a lip element 10 projecting linearly beyond each end, the width of said lip being proportioned so that it may be inserted through the upper portion of the previously described slot.

Into the forward edge of said lip, at substantially its juncture with the main body portion of the rail 9, there is a rearwardly directed notch, slit or recess 11 whose depth is approximately equal to the distance from the forward end of the slot through the flange 4 to the adjacent front edge 3 of the side wall.

With the slot so sized and shaped, and the lip constructed as aforesaid, the width of said lip is too great to permit entry through the lower portion of the slot, but is insertible through the upper portion of the latter. After insertion of the lip through said upper slot portion, the rail may be shifted forwardly whereupon the slit 11 will receive and straddle the flange material forwardly of the front end of said slot, until the closed end of said slit abuts said closed forward slot end, or the forward edge of the lip abuts against the inside of the front edge element 3, as the case may be, whereupon the lip may be lowered at its rear edge to be received in and be firmly seated in the lower portion of the slot. The flange 4 is also provided with a cut-out

12 extending vertically upwardly from a slight distance above said slot, being open at the rear-most edge of said vertical flange and closed and terminating a slight distance forwardly of the rearmost end of the upper portion 8 of the slot.

The instant invention is especially intended for use with a suspension type of cabinet, that is one wherein the drawers are mounted to slide on carriers that are in turn slidably mounted on the slide rails previously mentioned.

There is a pair of such slide rails for each front rail mentioned, one such slide rail at each side wall, for connection to one end of the front rail. The slide rail 6 is provided with a tongue element 13 at the end that is to be connected to the front of the cabinet, said tongue being struck up from the metal of the approximately channel-shaped cross-section slide rail, and being substantially coextensive with said slide rail end therat.

The line of juncture of said tongue and slide rail body is indicated at 14 and is slightly narrower than the rail thereat, and the distance that the tongue is struck up from the rail metal is sufficient to permit the flange 4 to be received in said space. The distance of the juncture line 14 from the adjacent forward end of the slide rail is such that when said rail is shifted forwardly, with the forward or closed end of the cut-out straddled between the tongue and rail body portion, such shifting will be limited by the abutment of said rail abutting along said juncture line, with the forward end of the cut-out, and whereupon that portion of the slide rail below and forwardly of said juncture line will overlap the rearmost portion of the upper slot portion 8.

Assuming that the front rail has been inserted through the upper portion of the slot through the flange and then shifted forwardly and lowered and seated in the lower slot portion, the assembling of the slide rail element in the foregoing described manner will be sufficient to bring the slide rail to be supported on the already seated front rail, and the overlapping portion of the slide rail will close the rearward portion of said slot sufficiently to limit tilting of said lip element and prevent withdrawal of the lip element 13 from the slot.

If desired, additional securement between the several parts may be secured by a spot weld 15.

Having thus described my invention, it is obvious that various immaterial changes and modifications may be made in the same without departing from the spirit of my invention; hence I do not wish to be understood as limiting myself to the exact form, arrangement, construction and combination herein shown and described, nor the uses mentioned, except as limited by the state of the art to which this invention appertains and by the claims hereunto appended.

What I claim as new and desire to secure by Letters Patent is:

1. In a filing cabinet provided with a vertical side wall, a horizontal front rail and a slide-receiving rail extending from front toward the rear of said side wall, a joint structure interlocking said parts together and comprising a horizontally elongated slot through said wall adjacent its front, with the upper portion of said slot extending rearwardly beyond the lower portion thereof, said front rail having an end portion insertible through the upper portion of said slot but not through the lower portion thereof, there being a recess in said rail end portion extending rearwardly and opening at its front edge and whereby

75 said rail end portion may be inserted through said upper slot portion and the rail then shifted forwardly, with said recess straddling said side wall, and the front rail then lowered into said lower

5 slot portion to seat thereinto, said slide-receiving rail having a tongue struck from the front end of its main body portion with the rear of said tongue being rearwardly of said front end of said slide-receiving rail so that the adjacent portion of said 10 side wall may be straddled between said tongue and the main body portion of the slide-receiving rail and the latter rail supported on said finally seated lowered front rail.

2. The combination and arrangement of elements as recited in claim 1, but characterized in that the attached end of said tongue is rearwardly of the adjacent free end of the slide-receiving rail a sufficient distance so that the slide-receiving rail rests on said seated front rail and 15 extends sufficiently forward beyond the rear end of said upper slot to close said rear end of the upper slot portion.

3. The combination and arrangement of elements described in claim 1 but further characterized in that the side wall has a cut-out extending vertically from a point spaced above the rear end of the upper slot portion and with the depth of said cut-out extending forwardly beyond the rearmost end of said upper slot portion, and further characterized in that the attached end of said tongue is rearwardly of the adjacent free end of said slide-receiving rail a distance approximately equal to the depth of said cut-out, and with said tongue narrower than said adjacent free end of said slide-receiving rail, so that after the front rail has been seated on the bottom portion of the slot, the slide-receiving rail may be shifted forwardly until the tongue rear end abuts that portion of the side wall material that defines the front edge of said cut-out, and the slide-receiving rail end rests on said seated front rail and closes said upper portion of the slot.

4. In a filing cabinet provided with a vertical side wall having a relatively narrow reentrant flange spaced therefrom and extending along its front, a horizontally extending transverse front rail and a slide-receiving rail extending from front to rear of said side wall, a joint structure interlocking all of said parts and including an approximately horizontally extending slot through said flange and whose closed ends are spaced from the adjacent front and rear ends of said flange, said slot enlarged vertically toward its rear and with the upper portion of the slot extending rearwardly beyond the adjacent lower portion of the slot, said flange provided with a vertically elongated cut-out spaced above said slot and open at the rear and extending forwardly past the rear end of said upper slot portion, one end of said front rail provided with a linearly projecting lip along its front edge and of such size that it is insertible through the upper slot portion only, said lip having a notch at its juncture with the rail body, said notch open at its front edge and extending rearwardly a distance substantially equal to the spacing between the flange front edge and the adjacent end of the slot, whereby said front rail may be assembled in place by inserting said lip through the upper portion of said slot and then shifted forwardly while the flange material is straddled by said notch, and said lip then lowered to seat on the bottom slot portion at substantially the forward limit of said shifting, said slide-receiving rail having a tongue struck up at one end and whose

free end terminates substantially co-extensive with the rail end, the lower edge of said tongue at its juncture with its rail being spaced such a distance above the lower edge of its rail that when said forward edge of the cut-out is straddled between said tongue and adjacent rail portion and the slide-receiving rail then shifted forwardly until the rear end of the tongue abuts against said cut-out forward edge, the slide-receiving rail will be supported on said front rail and overlap 10 said upper slot portion sufficiently to limit tilting

of the lip and prevent withdrawal of the lip through said slot.

JACK ADLER.
